UNITED STATES PATENT OFFICE.

MARY MILLER, OF THERESA, WISCONSIN.

BROODER.

1,262,541.

Specification of Letters Patent.

Patented Apr. 9, 1918.

Application filed October 13, 1917. Serial No. 196,536.

To all whom it may concern:

Be it known that I, Mrs. MARY MILLER, a citizen of the United States, residing at Theresa, in the county of Dodge and State 5 of Wisconsin, have invented new and useful Improvements in Brooders, of which the following is a specification.

This invention is an improved brooder, the object of the invention being to provide 10 a brooder of novel construction, which is cheap and simple, which is portable and may be readily and easily cleaned, and which avoids the use of a lamp or heating device of any kind in which fuel is consumed, so that all danger of setting fire to 15 the brooder and to the building in which the same is used is entirely avoided; another object being to provide an improved brooder in which the temperature can be readily 20 maintained at the desired point and which affords thorough ventilation and keeps the chicks warm and comfortable and under such conditions as to greatly promote their growth and development.

25 The invention consists in the construction, combination and arrangement of devices hereinafter described and claimed.

In the accompanying drawings:—

Figure 1 is a perspective view of a brooder 30 constructed and arranged in accordance with my invention.

Fig. 2 is a longitudinal sectional view of the same.

Fig. 3 is a transverse sectional view of the 35 same.

Fig. 4 is a detailed plan of the heating tank.

My improved brooder comprises a bottom 1, a roof 2, end walls 3, a front wall 4 and 40 a rear wall 5. The roof, walls and the bottom are made of suitable lumber, usually three-fourths of an inch thick, and lined on the outside with water proof paper or other suitable water proof material, indicated at 6, and covered with galvanized iron as at 7 and are also lined on the inside with a double thickness of water proof paper as at 8. Blocks 9 are secured under the corners of the brooder to raise the bottom thereof 45 above the floor or ground and to permit air to circulate beneath the brooder to keep the same dry and promote the healthfulness of the chicks. An entrance opening at 10 is in the front wall of the brooder at a point 50 near the center thereof and may be covered by means of a slide 11 which is preferably

made of galvanized iron. The rear wall 5 of the brooder has an opening 12 of suitable size and a slide 13 to close said opening. On the ends of the brooder are handles 14 60 each of which comprises a bar 15, the ends of which are secured on bracket blocks 16 so that the handle bars are spaced from the end walls of the brooder as shown. Each end wall has a ventilating opening 17 near 65 the top and a slide 18 to cover or partly cover said opening as may be desired.

The brooder is gabled and the top or roof comprises a front member 19 and a rear member 20. The rear member is firmly secured. The front member is hinged, at the ridge, to the rear member as at 21 so that the front member can be raised or lowered, to open or close the brooder, as may be desired. In the ends of the front member are 75 openings 22 which are provided with glass panes 23 to admit light. The ridge of the roof may be closed by a galvanized iron ridge cap 24.

The brooder is heated by heat radiated 80 from a tank 25 which contains hot water. The tank is of suitable capacity and proportion according to the size of the brooder and is preferably made of galvanized iron, is of oblong rectangular form and is provided 85 at one side, at the center, with an arm 26 which projects therefrom and enables the tank to be filled or emptied, a filler opening and nipple 27 therefor being provided at the top of the arm and an emptying opening 90 and nipple or closure 28 therefor being provided near the bottom and at the outer side of the arm. On the top of the tank is a valve 29 to promote the escape of steam from the tank after the same has been freshly 95 filled with boiling water, if desired and to regulate the heating effect of the tank by opening or closing the valve, as will be understood. The tank has hollow ends 30 to enable the tank to be readily handled by 100 grasping the same at the ends. The top, sides and ends of the tank are covered with non-conducting material 31 such as heavy perforated ridged or corrugated paper and the bottom of the tank is covered with 105 paste-board or other suitable insulating material 32. An outer covering 33 of canvas is secured around the tank and is sewed with binding cord at the back and at the ends of the tank.

110 The tank is arranged in the brooder, is movable therein and removable therefrom,

and when in place is supported on bars 33 which extend transversely across the brooder and the ends of which are supported on strips 34 which are secured on the opposing 5 sides of the front and back of the brooder and at a height of about nine inches above the floor or bottom so that the tank is supported at an appropriate height above the bottom of the brooder and substantially in 10 the center thereof and heat radiated from the tank extends to all portions of the brooder and the same is heated at all points to a substantially even degree of temperature. The arm 26 of the tank is arranged 15 opposite the opening 10 and when it is desired to empty the tank and to refill the same with hot water the tank is moved at the back of the brooder so that its arm 26 is caused to project through the opening 12 20 thus exposing the filling and emptying nipples and enabling the tank to be emptied and refilled without the necessity of removing the tank from the brooder and without danger of spilling any water in the brooder. 25 When the tank is removed from the brooder the bars 33 may be also removed so that the interior of the brooder is entirely unobstructed and the same may be readily and thoroughly cleaned. Preferably the bottom 30 of the brooder is covered by a piece of removable fabric 35, such as roofing fabric or the like, which may be readily taken out of the brooder and cleaned. A piece of pasteboard 36, or other suitable material, may be 35 placed over the tank and a blanket 37 or

other suitable fabric may be placed over said paste-board and arranged with its ends hanging down therefrom within a few inches of the bottom of the brooder, to concentrate heat in the center of the brooder 40 under the tank and to allow chicks to pass freely either to the more highly heated space or to the ends of the brooder as they may desire.

My brooder is extremely cheap and simple, may be readily moved from place to place, may be readily cleaned and kept supplied with hot water, is not liable to injure the chicks and is entirely free from danger of starting a fire as the use of a lamp or 45 other dangerous heating medium is entirely avoided.

While I have herein shown and described a preferred form of my invention, I would have it understood that changes may be 50 made in the form, proportion and construction of the several parts without departing from the spirit of my invention and within the scope of the appended claim.

Having thus described my invention, I 55 claim:—

A brooder structure having an opening in one of its walls and a heating tank in the structure and movable toward and from said wall, said tank having an arm adapted to 60 project through said opening when said tank is arranged near said wall and being provided with filler and emptying means.

In testimony whereof I affix my signature.

MRS. MARY MILLER.
